UNITED STATES PATENT OFFICE.

JOHN B. F. HERRESHOFF, OF BROOKLYN, NEW YORK, ASSIGNOR TO HIMSELF,
WILLIAM H. NICHOLS, AND GEORGE H. NICHOLS, ALL OF SAME PLACE.

PULLEY-BLOCK.

SPECIFICATION forming part of Letters Patent No. 304,103, dated August 26, 1884.

Application filed May 22, 1884. (No model.)

To all whom it may concern:

Be it known that I, JOHN B. F. HERRESHOFF, of Brooklyn, county of Kings, and State of New York, have invented an Improvement 5 in Pulleys for Hoisting Apparatus, of which the following is a full, clear, and exact description, reference being made to the accompanying drawings.

My invention relates to improvements in 10 hoisting-pulleys, which consist, first, in placing the axle of the sheave in adjustable metal boxes having long bearing-surfaces, so as to make long bearings for the axle; secondly, in connecting these boxes to a forked metal strap, 15 in such a manner that when one part of their inner surface is worn by the friction of the axle they may easily be turned so as to present a new bearing-surface; and, thirdly, in attaching to this forked metal strap, which 20 straddles and supports the sheave, a tongue which projects downwardly into the groove of the sheave and prevents the rope from slipping off.

In the accompanying drawings, which clearly 25 show my invention, Figure 1 is a side elevation; and Fig. 2, a section on the line *c c*, Fig. 1.

The sheave A is rigidly mounted upon a long axle, B, the ends of which enter metal pockets or boxes C, each of which is provided with 30 an opening, *a*, to allow of the axle being oiled. These boxes C are held in place by the forked suspension-strap D, to which they are secured by screws *d*. This forked strap passes over the sheave, and is provided at its upper part 35 with a hook, *e*, or other suitable means, by which it may be suspended from a hoisting-

gaff or other beam or holder. Should the boxes C become worn so as to allow the sheave to shake, it is only necessary to loosen the screws *d*, turn the boxes so that a new bearing-surface is presented, and again to tighten the screws. As this may be repeated a considerable number of times, it may easily be seen that this pulley will outlast a great number of the old kind, which were entirely useless after the holes in their shells were once worn.

To prevent the rope F from slipping, I attach to the forked strap D a tongue, E, which projects downwardly into the groove of the 50 sheave, forming a channel, within which the rope F is confined. The strap D holds the boxes C stationary, straddles the sheave A, and allows the axle B to revolve freely within said boxes.

I claim—

1. The combination of the metal boxes C with the forked strap D, axle B, and sheave A, substantially as and for the purpose specified.

2. The combination of the metal boxes C with the sheave A, axle B, strap D, and clamping-screws *d*, substantially as and for the purpose specified.

3. The combination of the tongue E with the forked strap D and grooved pulley A, substantially as and for the purpose specified.

JNO. B. F. HERRESHOFF.
